[57] ABSTRACT

A prefabricated flight deck is mounted on a framework above an offshore drilling platform to accommodate the landing of aircraft thereon. The flight deck has a plurality of lightweight honeycomb-type panel sections each formed of outer and inner skin members with honeycomb core and reinforcing beams sandwiched between the skin members and provided with lift stations. The panel sections are united together at complementary stepped joint surface areas which are both adhesively joined and mechanically fastened at spaced intervals to form an integral unit which is covered with an outer protective layer forming a sealed non-porous top surface. In a preferred form the deck is generally polygonal in shape and the panel sections are pie-shaped and extend radially with truncated inner ends thereof forming a central opening. A round center panel section fills the center. A safety fence projects outwardly from the outer ends of the panel sections for added surface area beyond the prefabricated deck.

PREFABRICATED FLIGHT DECK STRUCTURE FOR OFFSHORE DRILLING PLATFORMS

This invention relates to flight deck apparatus for landing and take-off of aircraft and more particularly to novel and improved lightweight flight deck structure for offshore drilling platforms and the like.

Offshore drilling platforms for drilling and pumping underwater wells support a drilling rig and the necessary equipment and personnel loading for operating same. Some offshore drilling platforms have a power unit to propel the platform to the point of destination and extensible and retractable jack-type legs to anchor the platform to the floor of a body of water. The large amount of personnel and equipment are required for continued operation of drilling rigs which necessitates prompt and efficient transportation of cargo to and from the platform. Of particular importance is the ability to establish aircraft flights to and from the drilling platform with safety and ease of take-off and landing especially during high winds. Some attempts have been made to provide steel flight deck structure on the platform but the loading capacity of a floating platform structure severely limits the size of a steel deck. In an application entitled *Prefabricated Building Structure For Off-Shore Crew Quarters and The Like*, Ser. No. 792,475, now U.S. Pat. No. 3,636,667 assigned to the assignee of the present invention, there is described a prefabricated flight deck forming the roof of the building structure.

Accordingly, it is an object of this invention to provide a novel and improved prefabricated sandwich-type flight deck structure for offshore drilling platforms and the like.

Another object of this invention is to provide a novel prefabricated flight deck assembly mounted on a structural framework which projects laterally out and away from the usable or working surface of the platform so as not to unduly occupy or materially interfere with the platform, thereby avoiding danger to aircraft and personnel of landing on the platform.

A further object of this invention is to provide a novel prefabricated flight deck made up of prefabricated honeycomb core-type panels which are substantially lighter than structural steel flight deck structures.

Yet another object of this invention is to provide a prefabricated flight deck structure characterized by ease of fabrication and assembly at the point of intended use and is readily mounted at different desired levels either directly on the platform or on a derrick on the platform.

Yet a further object of this invention is to provide a novel prefabricated flight deck which mounts directly on a horizontal framework and is made up of lightweight prefabricated panels united together to form an integral unit which is covered with an outer protective layer to form a sealed non-porous surface.

In accordance with the present invention in a preferred form shown, a prefabricated flight deck assembly is mounted on and affixed to a support framework above the platform, the support framework projecting horizontally beyond a side edge of the platform. The flight deck is made up of a plurality of prefabricated panel sections mounted on and projecting horizontally beyond the support framework, the panel sections having complementary stepped joint surface area joined by an adhesive, together with fastener members extending

through beams along the joint surface areas at spaced intervals to form an overlapping joint. A preferred form shown is of a generally polygonal shape and is made up of radial pie-shaped panel sections and a circular center panel section. Each panel section has a plurality of spaced lift stations to facilitate its being lifted into position by a crane or the like for the assembly thereof. Each panel section is composed of upper and lower skin members, preferably wooden, with honeycomb core and reinforcing beams sandwiched between the skin members. An outer protective layer, preferably fiberglass, covers the exterior surfaces of the joined panel sections to form a sealed non-porous top layer on the deck. Outrigger or safety fence structure is attached to the periphery of the deck to provide increased surface area.

Other objects, advantages and capabilities of the present invention will become more apparent as the description proceeds taken in conjunction with the accompanying drawings, in which:

FIG. 1 is a side elevational view of a jack-up offshore drilling platform having a prefabricated flight deck structure embodying features of the present invention mounted therein;

FIG. 2 is a top plan view of the prefabricated flight deck assembly of FIG. 1;

FIG. 3 is a sectional view taken along lines 3-3 of FIG. 2 showing a joint of the deck assembly along adjacent of the side edges of the radial panel sections;

FIG. 4 is a sectional view taken along lines 4-4 of FIG. 3 showing the manner of fastening the deck assembly to the support frame beams at a joint;

FIG. 5 is a top plan view of one of the pie-shaped radial panel sections of the flight deck assembly shown in FIG. 2;

FIG. 6 is a sectional view taken along lines 6-6 of FIG. 5 showing the details of the lift or pickup points for each radial panel section;

FIG. 7 is a top plan view of the center panel section for the flight deck assembly shown in FIG. 2;

FIG. 8 is a sectional view taken along lines 8-8 of FIG. 7 showing a joint between the radial panel sections and the center panel section; and

FIG. 9 is an enlarged side elevational view showing the connection of the outrigger structure to the deck assembly shown in FIG. 2.

Referring now to the drawings, in FIG. 1 there is shown a jack-up type drilling rig designated generally by numeral 10 comprising a floatable platform 11 carrying equipment used for offshore drilling operations and typically includes upright derricks 12 and 13, a jack house 14, a crane boom 15, a control house 16, and the like. The platform 11 is provided with a propulsion unit 17 at the rear to propel it through the water to a desired location. A plurality of extensible and retractable jack-up leg units 18 depend from the platform and are extensible to a selected depth to secure or anchor the rig to the floor of a body of water at the desired location. For the type shown mechanical gearmotors and gears with suitable controls are used to advance and retract the legs. The jack-up assembly of the type shown is capable of anchoring the platform in up to 300 feet of water. The configuration of the platform 11 (as viewed in the plan) may be generally triangular, rectangular, or of other desired shapes. In the triangular form the jack-up leg units 18 are disposed inwardly

of each apex or corner to form a balanced support for the platform.

A cantilever-type steel support framework 21 mounts at the edge of the platform. It is understood, however, that the support framework may mount on a derrick on the platform if required. As best seen in the side elevational view, the support framework 11 includes a lower section 22 made up of interconnected spaced upright columns and an upper section 23 made up of horizontally disposed spaced beams disposed in a common horizontal plane. These upper and lower framework sections 22 and 23 have an inner part directly above the platform and an outer part projecting outwardly from a side of the platform over the water to give the cantilever effect. As viewed in plan, the upper section 23 is generally of a polygonal shape and includes spaced parallel longitudinal beams 24 at right angles to the side edge of the platform, spaced parallel transverse beams 25 connected to the longitudinal beams, and periphery beams 26 which join the ends of adjacent of the longitudinal and transverse beams. The upper truss section 23 shown is essentially an eleven-sided configuration made by using essentially a twelve-sided polygon configuration with the two sides closest to the platform being made as one side extending parallel to the side edge of the platform and are suitably fastened thereto by bolts or the like.

The prefabricated flight deck assembly 30 is mounted on the upper horizontal section 23. This prefabricated flight deck assembly 30 shown is of a generally polygonal shape and is made up of a plurality of generally pie-shaped radial panel sections 31 having the inner ends cut off or truncated and a prefabricated center panel section 32 which fits into a central aperture formed by the truncated ends of an assembly of the pie-shaped panel sections. Outrigger structure 33 in the form of a safety fence projects outwardly from the outer edge of the pie-shaped panels to provide added surface area beyond the prefabricated part of the deck.

Each pie-shaped radial panel section 31 comprises upper and lower skin members 35 and 36, respectively, each made of plywood or the like having an inner honeycomb core 37 and wooden reinforcing beams sandwiched between the skin members which extend throughout the entire length of the skin members. The reinforcing beams include side beams 38 and 39, an inner end beam 41 and an outer beam 42 which together form a peripheral frame. The side beams 38 and 39 have outer end portions 38' and 39', respectively, which project beyond the outer ends of the skin members and inner core, and inner end portions 38'' and 39'' respectively, which project beyond the inner ends of the skin members. Adjacent side beams are fastened together at both inner and outer ends as described more fully hereinafter. The reinforcing beams preferably are made of two or more laminated boards or timbers secured together with an adhesive or glue along a common side. More specifically the honeycomb core for each panel section shown includes a pair of upper and lower honeycomb sections 37a and 37b separated by a relatively thin plywood sheet 43 which is glued to the honeycomb core as shown in FIG. 4 but the details of the core has been omitted from the other Figures for clarity.

Lift stations generally designated 45, 46 and 47 are provided at three different points on each radial panel

section 31 to facilitate the lifting thereof by an overhead crane or the like. Outer lift stations 45 and 46 are located inwardly of the wider outer end and spaced from one another and the inner lift station 47 is located 5 inwardly of the narrower inner end for a balanced three-point lift capability. Each lift station is defined by reinforcing the panel section with two groups of spaced pairs of intermediate reinforcing beams 48 and 49 extending parallel to one another and parallel to the end beams 41 and 42. A tubular member 51 preferably made of PVC or a like plastic tubing extends upwardly through the pair of intermediate reinforcing beams and is secured thereto preferably by an adhesive to the ends of both skin members in a sealed relation thereto. A tubular housing 52 having a lower flanged portion 52a and internal threads extends up through or telescopes 10 in the tubular member 51. Housing 52 is fastened along the underside by bolts 53 which thread into the adjacent intermediate reinforcing beams 48 and 49. The heads of the bolts 53 are recessed in the lower skin member. An externally threaded eyebolt 54 threads 15 into the internal threads in the flanged housing 52 and a cable or the like depending from the crane boom is suitably secured to each eyebolt to lift the panel into 20 place on the framework in the assembly thereof.

As best seen in FIG. 3, an outer timber 38a makes up 25 a part of the entire side beam on one side of each radial panel section 31. Timber 38a is approximately half the vertical extent of two other inner sandwiched timbers 38b and 38c which extend the full height of the core to 30 form an inwardly stepped joint surface area which is complementary to that of the adjacent radial panel section having the outer timber 39a in an offset position relative to timber 38a and secured to inner sandwiched timbers 38b and 38c. The abutting joint surface areas 35 are secured together by an adhesive along a glue line represented at 56. Fasteners 57 in the form of bolts are disposed at spaced intervals along the joint and extend 40 downwardly and are angularly inclined laterally with each bolt extending through the upper skin member and both narrower timbers of the abutting laminated beams to draw the stepped joint surface areas together along the glue line. For the deck shown the fasteners 57 are located at two-foot intervals. The head of each fastener 57 is recessed or countersunk into the outer skin member 35 and in the assembly of the panel section this recess is filled with a resin paste 58 or the like.

The inner ends 38'' and 39'' of a pair of abutting 45 panel sections 31 are further fastened by a pair of bolts 59a which pass transversely therethrough and in turn the outer ends 38' and 39' are fastened by bolts 59b for added strength.

The center panel section 32 closing the center area 55 of the deck comprises a generally circular outer skin member 61, a circular inner skin member 62 of a lesser diameter than the outer skin member, and a honeycomb core 63 and side reinforcing beams 64 sandwiched between the inner and outer skin members, the outer side reinforcing beams 64 being sandwiched between the inner and outer skin members. The outer side reinforcing beams 64 are made of two timbers laminated together and arranged in a five-sided configuration, as best seen in FIGS. 57 and 58. The honeycomb core 63 is the same as core 37 shown in FIG. 4. An upper reinforcing beam 65 made up of two boards is disposed between the outer skin member and outer side beams 64. Inner side reinforcing beams 66 made up of 60 65

two laminated timbers are spaced from the outer side beams to form a space 67. The glue line for the joint between the radial panel section and center panel section is represented at 70. This center panel section provides an assembly which is readily inserted into the central aperture of the assembly of pie-shaped members and is secured thereto by an adhesive and three spaced bolt fasteners 68 which extend vertically down through the beams of the center panel and into the radial panel sections 31, the heads of the fasteners being recessed in the outer skin member and filled with a paste 58.

The assembly of pie-shaped panels and center panel section making up the deck are provided with an outer protective coating or layer 69 which covers all of the exposed surfaces defining an essentially seamless non-porous top deck surface. The top deck surface is preferably fiberglass material which may be sprayed or otherwise applied in a bonded relation to the outer skin of the panels and may be applied to a desired thickness. As employed therein, the term "fiberglass" has specific reference to glass fibers bonded together as a suitable bonding agent such as a synthetic resinous compound which is applied to the prefabricated panel sections and will cure into a firm bonded relation to the underlying surface.

The outrigger structure or safety fence 33 is made up of a series of interconnected box-shaped side frame members 71 and inner and outer corner frame connectors 72a and 72b arranged along the outer periphery of the deck. The side frame members comprise an inner bracket 73 having a generally right-angle cross-section which fits against the upper outer corner of the deck and is secured thereto by a top and outer fasteners 74 and 75, respectively, shown as being bolts which thread into the wooden beams. A main tubular portion 76 extends outwardly and upwardly at a slight angle from each bracket 73. Inner and outer tubular portions 77 and 78 connect at the inner and outer ends of the main tubular portion and to a next adjacent main tubular portion 76 to form a box-shaped framework. The outer corner frame connectors 72b provide extensions for tubular portion 78 and the inner corner frame connector is disposed outwardly to inner tubular portion 77 to accommodate the corners of the polygonal shape. The connected frame members 71 and 72 are covered with a layer of galvanized wire 79 such as chain link and a top layer of fabric 80 such as canvas is laced over the wire or the like.

As best seen in FIG. 4, the prefabricated deck is fastened to the support framework beams by a hold-down fastener in the form of a bolt 81 which extends down through tubular members 82 in each beam panel section and through a top truss beam 24. The tubular members preferably are of a PVC material or the like and the heads of the bolts are recessed in the top skin member so that after assembly the recesses are filled with a resin 83 prior to applying the outer protective layer. The fasteners 81 are located at spaced intervals where the joints of the deck overlay a top support truss beam.

A prefabricated deck utilizing the fiberglass sandwich panel above described is of substantially less weight than that of comparable steel flight decks. For example, a prefabricated deck made in accordance with the present invention had approximately twice the surface area of that of steel deck for the same weight. This is an increase in the loading strength to deck

weight of about two to one, affording a significant advantage over comparable steel flight decks for floating platform applications.

While a generally circular or polygonal deck configuration is shown, it is understood that the present invention is also applicable to rectangular deck shapes using an assembly of rectangular panel sections.

Although the present invention has been described with a certain degree of particularity, it is understood that the present disclosure has been made by way of example and that changes in details of structure may be made without departing from the spirit thereof.

What is claimed is:

1. In a flight deck structure for an offshore platform and the like for the landing and take-off of aircraft, the combination comprising:

a cantilever support framework mounted above and projecting outwardly in a horizontal direction beyond the platform,

a prefabricated flight deck assembly mounted on said support framework including a plurality of prefabricated panel sections united together to form an integral unit, each panel section including upper and lower skin members and a honeycomb core and reinforcing beams sandwiched between said skin members, adjoining sides of said panel section having complementary stepped joint surface areas secured together with an adhesive to form an overlapping joint, fastening members extending through the stepped joints at spaced intervals along each joint to further hold abutting panel sections together, an outer protective layer covering the exterior surfaces of said joined panel sections to form a sealed, non-porous upper deck surface, and

lift station means including spaced points of support for each said panel section, each point of support being defined by a pair of reinforcing beams sandwiched between said skin members, a tubular member extending vertically through the panel between the beams, and a flanged member with internal threads telescoping in the tubular member adapted to threadingly receive an eyebolt.

2. In a flight deck structure as set forth in claim 1 wherein said framework includes a network of horizontal beams arranged in a preselected configuration to which the deck assembly is fixedly secured, said deck assembly projecting horizontally and outwardly beyond said support framework.

3. In a flight deck structure as set forth in claim 1 wherein said panel sections are preshaped, said skin members and beams are wooden and said outer layer is fiberglass.

4. In a flight deck structure as set forth in claim 1 wherein said panel sections and skin members have inner and outer ends and said reinforcing beams extend beyond the outer ends of the skin members, and fastening members passing transversely through both the inner and outer ends of abutting panel sections to fasten abutting panel sections together along the side edges thereof.

5. In a flight deck structure as set forth in claim 1 wherein said fastening members for the stepped joints are in the form of bolts extending downwardly and are angularly inclined laterally between abutting reinforcing beams of each of the adjacent panel sections, the upper head end of said bolts being recessed in the panel

section and the recess covered with a sealing filler material.

6. In a flight deck assembly as set forth in claim 1 wherein each said panel section has lift station means to facilitate its being lifted into place on the support framework. 5

7. In a flight deck assembly as set forth in claim 6 wherein said lift station means are at three spaced points in a triangular configuration on each panel section. 10

8. In a flight deck assembly as set forth in claim 1 wherein each said panel section has tubular members extending vertically therethrough and in sealed relation to the skin members, honeycomb core, and outer layer to slidably receive fasteners to facilitate the fastening 15 of the deck to the support framework.

9. In a flight deck assembly as set forth in claim 1 wherein said panel sections are essentially pie-shaped having truncated inner ends and extending radially and outwardly from the inner ends, and a center panel section united to the inner ends of the radial panel sections to form a generally circular deck structure. 20

10. In a flight deck structure as set forth in claim 1 wherein said support framework is of the cantilever type and projects outwardly from a side edge of the platform to dispose a substantial portion of the flight deck over the water, and said deck assembly projects horizontally beyond said support framework. 5

11. In a flight deck structure for an off-shore platform and the like for the landing and take-off of air draft, the combination comprising: 30

a cantilever-type support framework including a network of connecting horizontal beams forming a top section of a preselected configuration and a network of connected columns forming a lower section, and 35

a prefabricated flight deck secured on the top section including a plurality of radially extending, generally pie-shaped, prefabricated, radial panel sections projecting horizontally beyond said support framework and a generally circular center panel section united to said radial panel sections to form an integral unit therewith, each of said radial and center 40

panel sections including upper and lower skin members and a honeycomb core and reinforcing beams sandwiched between said skin members, adjoining sides of said radial and center panel sections having complementary stepped joint surface areas secured together with an adhesive to form overlapping joints, fastening members extending through the overlapping joints at spaced intervals along the joints of the radial panel sections to further hold abutting radial panel sections together, fastening members connecting the inner and outer ends of abutting radial panel sections together, and an outer protective layer covering the exterior surfaces of said joined panel sections to form a sealed, non-porous upper deck surface.

12. In a flight deck structure as set forth in claim 11, wherein said center panel section has a lower skin member of lesser diameter than said upper skin member, said center panel section having a reinforcing member under said upper skin member along the side edge thereof forming a stepped joint surface area. 20

13. In a flight deck structure as set forth in claim 12 including fasteners extending vertically through the center panel section and into the radial panel sections at the joint thereabove to fasten said radial panel sections with said center panel sections. 30

14. In a flight deck structure as set forth in claim 11 wherein said center panel section has peripheral reinforcing beams sandwiched between the skin members forming a part of the stepped joint surface area and arranged in an annular configuration, each peripheral beam spanning a number of radial panels. 35

15. In a flight deck structure as set forth in claim 11 including an outrigger structure projecting outwardly from the periphery of the deck assembly for added surface area. 40

16. In a flight deck structure as set forth in claim 13 wherein said outrigger structure includes a plurality of box-shaped frame members having a bracket at the inner end secured directly to reinforcing beams along the outer edges of the panel sections. 45

* * * * *
